POWER

Oswald Duda, Corsicana, Tex., assignor to American Well & Prospecting Company, Corsicana, Tex., a corporation

Application August 10, 1935, Serial No. 35,637

1 Claim. (Cl. 74—606)

This invention relates to a power and has more particular relation to that type of power particularly designed for use in operating oil wells in an oil field from a central location.

Another object of the invention is to provide, in an apparatus of the character described, a rotary table mounted to turn about a stationary spindle and having thereon an eccentric spindle mounted to revolve about the stationary spindle with a disk having a bearing on the eccentric spindle and which is thus mounted to oscillate about the stationary spindle, and forming a connection for the rods leading to the various pump jacks for operating the well pumps.

The disk above referred to is of such novel design that the connections thereto of the rods leading to the pump jacks are in approximately the same horizontal plane as that of the bearing of the disk on the eccentric spindle and as that of the main bearing of the rotary table on the stationary spindle.

A further object of the invention is to provide a power of the character described wherein the relative locations of the rotary table bearing, the disk bearing, and the connections of the pump jack rods to the disk are such that the stress of the load will be exerted in approximately a straight line through said bearings, so as to conduct to uniform wear and to prevent a concentration of wear on said bearings.

With the above and other objects in view, the invention has particular relation to certain novel features of construction, operation, and arrangement of parts, an example of which is given in this specification, and illustrated in the accompanying drawings, wherein:—

Fig. 1 shows a vertical sectional view of the apparatus, and

Fig. 2 shows a plan view, partly broken away, and partly in section.

Referring now more particularly to the drawings, wherein like numerals of reference designate similar parts in each of the figures, the numeral 1 designates a casing having enclosed within it the gear case 2, which is enclosed above by a cover plate 3. Adjacent the gear case, the casing is formed approximately circular, forming the chamber 4 having the elevated horizontal partition 5, forming the bottom thereof. Supported on said partition there is the upstanding tubular spindle 6 having the wide base 7 which is secured to said horizontal partition by means of suitable screws, as 8.

There is a rotary table 9 forming a cover for the chamber 4, and whose margin is formed with

the downwardly turned flange 10 which fits closely around the upstanding circular wall around the chamber 4. The rotary table 9 is formed with a central sleeve-like hub 11 which fits over the spindle 6. The upper end of the hub is closed by the cap 12 which may be bolted thereto by means of the set-bolts 13. The upper end of the spindle 6 is reduced and between said reduced upper end and the hub 11 are the main roller bearings 14. The lower end of the hub 11 may also have roller bearings 15 between it and the base of the spindle.

The rotary table 9 is equipped with a suitable ring gear 16 which is enclosed within the chamber 4 and which is in mesh with a spur gear 17, 15 which is fastened on the sleeve 18. This sleeve rotates about a spindle 19 whose upper and lower ends are suitably anchored to the top and bottom of the gear case. Conventional anti-friction bearings are located between the sleeve 18 and the spindle 19 and fixed on the lower end of said sleeve 18, there is a bevel gear 20 which is in mesh with and driven by the pinion 21. This pinion is fixed on the inner end of the drive shaft 22, which rotates in suitable aligned bearings at one side of the gear case, and which is adapted to be connected to a source of power. The shaft 22 is equipped with suitable anti-friction bearings, as shown. Means are thus provided for driving the rotary table 9. The table 9 has an eccentric spindle 23 upstanding therefrom which revolves about the main bearings 14 as the table 9 turns.

There is a circular disk 24 which has the central hub 25 and this hub is fitted into and rotates in an upstanding bearing sleeve 26 which is formed eccentrically on, and upstanding from, the table 9. Within the hub 25 are the roller bearings 27 which surround the spindle 23. The upper end of the hub 25 is closed by a suitable cap plate 28 which may be bolted, or otherwise secured thereto, and between this cap plate and the upper end of the spindle are the anti-friction bearings 29 which are located between the upper and lower race plates 30, 31.

The disk 24 must be mounted to clear the upper end of the hub 11 of the rotary table so that said disk may be freely revolved.

As hereinabove indicated, the power will be located centrally with respect to the various wells, in the field, to be operated, and the operating rods, as 32, will radiate from said disk and will be connected at their outer ends at the various pump jacks and at their inner ends to the margin of the disk 24. The connection of each

rod 32 to the disk 24 is effected by means of a yoke 33 which is clamped to said rod and which embraces the margin of the disk and is pivotally connected thereto by the connecting pin 34, as shown in Fig. 1.

In order that the line of thrust of the rods 32 may pass through the bearings 14, 27, intermediate their ends so as to prevent any undue stress on said bearings, and to cause the wear to be distributed through the lengths of the bearings, the margin 35 of said disk 29 is downwardly turned and is provided with bearings 36 to receive the pins 34 which connect the various yokes 33 to the disk 24.

It is obvious that as the table 9 rotates, the disk 24 will be correspondingly revolved, or oscillated, and the connecting rods 32 will be reciprocated, thus operating the various pump jacks and pumps to which the rods are connected.

The gear case 2 and the chamber 4 will be kept filled, or partly filled, with oil for lubricating purposes. The gears 16, 17, 20, 21, as well as the bearings 15 and the bearings of the shaft 22 will be thereby directly lubricated. A conventional pump 37 is located in the gear case and is operated from the shaft 22 and this pump forces the lubricant through the pipe 38 into the tubular spindle 6, and the lubricant overflows the upper end of said spindle, lubricating the spindle bearings and passes out through the duct 39 and up through the axial channel 40 of the spindle 23, and over-flows the upper end of the tube 41, which is located in a transparent shield 42. This overflowing lubricant flows back down and lubricates the bearings 29 and 27 and passes through the ports 43, 44, and on to the

teeth of the gears 16, 17, and thence back into the gear case 2. The pipe 38 has the branch 45 which conducts the lubricant to the bearings of the sleeve 18, and the oil finally flows back into the gear case. The lubricating system described, however, is not considered to be a part of the invention disclosed. 5

The drawings and description disclose what is now considered to be a preferred form of the invention by way of illustration only, while the broad principle of the invention will be defined by the appended claim. 10

What I claim is:

A power for operating well pump jacks comprising a bottom support, a tubular upstanding spindle having a bottom flange detachably supported on said support and whose upper end is reduced, a rotary table having a sleevelike hub, which extends above and depends beneath said table and fits over said spindle, upper, intermediate and lower bearings between the hub and spindle, an eccentric spindle upstanding from the table, a bearing sleeve surrounding and spaced from said eccentric spindle and upstanding from the table, a disc having a central hub which fits closely within said upstanding sleeve and which surrounds said eccentric spindle, bearings between the eccentric spindle and the hub of said disc, means for rotating the table to revolve the disc about the table spindle, the margin of the disc being downwardly turned and having attaching means for radially extending pump actuating rods, said margin being located in a plane passing through the disc bearing and the upper table bearing. 20 25 30 35
